(57) **CLAIM**

The ornamental design for an optical module with LED emitting amber-colored light, as shown and described.

DESCRIPTION

The patent or application file contains a least one drawing executed in color. Copies of this patent or patent application publication with color drawing(s) will be provided by the Office upon request and payment of the necessary fee.

FIG. 1 is a top perspective view of an optical module with LED emitting amber-colored light, showing our new invention;

FIG. 2 is a bottom perspective view of the optical module with LED amber-colored light of FIG. 1;

FIG. 3 is a first side view of the optical module with LED that emitting amber-colored light of FIG. 1;

FIG. 4 is a second side view of the optical module with LED that emitting amber-colored light of FIG. 1;

FIG. 5 is a third side view of the optical module with LED emitting amber-colored light of FIG. 1;

FIG. 6 is a fourth side view of the optical module with LED emitting amber-colored light of FIG. 1;

FIG. 7 is a top view of the optical module with LED emitting amber-colored light of FIG. 1; and,

FIG. 8 is a bottom view of the optical module with LED emitting amber-colored light of FIG. 1.

The broken lines in the drawings form no part of the claimed design.
